UNITED STATES PATENT OFFICE.

REVERE R. GURLEY, OF WASHINGTON, D. C.

DISTANCE-INSTRUMENT.

SPECIFICATION forming part of Letters Patent No. 359,073, dated March 8, 1887.

Application filed September 15, 1885. Serial No. 177,194. (No model.)

To all whom it may concern:

Be it known that I, REVERE R. GURLEY, a citizen of the United States, and a resident of Washington, (the Soldiers' Home,) in the District of Columbia, have invented certain new and useful Improvements in Measuring Devices, of which the following is a specification.

My invention relates to instruments for measuring distances, and it has for its object the production of a measuring-instrument that shall be simple of construction and reliable in use, and which shall be based upon a principle whereby complex calculations may be dispensed with in the measurement of distances.

The principle of which I make use in the construction of my measuring-instrument is the well-known geometrical law that lines drawn parallel to one side of a triangle, if sufficiently extended, produce sections of the two other sides that are proportional. The manner in which I employ this law will clearly appear from the following description, with reference to the accompanying drawings, in which—

Figure 1 shows a plan view of a structure in which my invention is embodied; Fig. 2, a side elevation of the same with the pivot and base-line bar partially in section, and Fig. 3 enlarged transverse section through the base-line bar and telescope-holder. Fig. 4 is an enlarged detached view looking in the direction of the arrow, Fig. 1. Fig. 5 is a modification. Fig. 6 is a diagram illustrating the principle of my invention and the mode of practicing the same.

Mounted upon a tripod or otherwise is a base-plate, B, having a base-line bar, B', pivoted thereto so as to be substantially parallel therewith. I have shown a conical pin, C, upon the under side of the bar, fitted into a corresponding socket in block C', which is secured to or made in one piece with the base-plate B. Any other suitable method of pivoting may, however, be employed. From the other end of the bar projects downward a short block, D, which supports the bar B' on the track Z. Above the block D is a block within the bar pivoted for rotation around a vertical axis. This block is engaged by the adjusting-screw S, locked against longitudinal motion by the blocks P and Q. The latter are free to move along the tracks parallel

to the prime position of the bar. Thus the line of the screw is always perpendicular to the prime position of the bar. Any method of securing the screw may, however, be employed which does not introduce too great an error. Thus, for example, D' and Q' may be used, the former passing through the base-line and the latter pivoted to the base-plate. This involves an error of about .00005; or D' may be free to move longitudinally within the bar and P and Q be secured to the base-plate, &c.—error of less than .00002.

The amount of motion of the bar may be determined by the distance between the threads of the adjusting-screw and the amount of rotation of same, or in any other suitable manner.

The base-line bar B' is slotted longitudinally for the reception of the traveling nut n', to which is secured the carriage E for the sighting-instrument. The axis of the latter makes, with the line of the bar B', an invariable (preferably a right) angle. A screw-rod, n, locked at the ends of the bar B' against longitudinal motion, engages the traveling nut, and by turning said screw the sighting-instrument may be adjusted to any desired position upon the base-line bar B'. By graduating the bar, or otherwise, the distance of the sighting-instrument from the end of the bar may be determined. If, now, an object be sighted through the sighting-instrument at the end of the bar C, and the bar be then moved through any angle, the object may be again sighted by traveling the instrument, by means of the screw-rod, a suitable distance along the bar.

In Fig. 6 the base-line bar B' is represented in its normal and its angular positions, and is divided into feet, (or other units of measure,) at a' b' c' d', &c., these points marking the distances of one two three four, &c., feet, (or other units of length,) respectively, from the pivotal point C. If now an object, a'', be sighted through the sighting-instrument at C, and the bar B' be then moved through an angle, o = Ca''a', to the position indicated by the broken line, then the object may be again sighted by moving the sighting-instrument by means of the screw-rod to a', for since o = Ca''a', a' is the point of intersection with C' of the line a'' a', which makes with C' an angle equal to that

included between the axis of the sighting-instrument and the bar, (the angle between the two being the same in both cases.) If the sighting-instrument be moved twice the distance from the pivotal point C—viz., to the point b' on the bar—an object, b'' , will be accurately sighted, the distance of which from C is twice as great as that of a'' from the same point, and if the distance of the sighting-instrument from the pivotal point be made three four..., or n times as great as the distance of a' from the same point the distance of the objects $c''d''$, &c., will be three four....., or n times as great as that of a'' , since the homologous sides of the similar triangles $Ca''a'Cb''b'Cc''c'Cd''d'$, &c., are proportional. It only remains to determine the angle o . For simplicity, suppose $tCa'' = 90$ degrees, $Ca'' = 5,280$ feet, $Ca' = 1$ foot, Ct' (the length of the bar B' , from the pivotal point C to the point of application of the adjusting-screw) to be 52.80 inches. Let the axis of the sighting-instrument be perpendicular to the line of the bar B' , and let Ct' be considered a right-angle triangle, since the length of the base-line bar is necessarily very small compared with the distances measured by the instrument, and the adjustment of the bar is therefore also very small, and the arc described by said bar is to all practical purposes a straight line and may be considered as at right angles to the base-line, thus greatly simplifying the solution of the problem without causing material error. Then $Ca' a''$ and $Ct' t$ are both right-angle triangles, and their homologous sides are proportional; hence $Ca' : Ca'' :: tt' : Ct'$, which, with the above figures, becomes $1 : 5,280 :: x : 52.80$, whence x or $tt' = .01$ inch. Thus the angle o is determined by its sine, and if a bar of the length of 52.80 inches be moved .01 inch, each foot of movement along such a bar from the pivotal point determines a distance of 1 mile in the field, and fractions and multiples of feet upon the bar determine

like fractions and multiples of miles in the field.

It is evident that the demonstration applied for simplicity to right angles applies equally to any angles whatever between the sighting-instrument and the bar, and also to any scale, whether of feet and miles or otherwise.

It is evident that the sighting-instrument may be pivotally mounted in the bearing and a graduated circle be attached, so that the altitude of objects may be easily deduced.

Compasses, levels, and all other attachments ordinarily applied to surveying-instruments may be applied in an obvious manner.

I claim—

1. A measuring-instrument consisting of a base-line bar pivoted at one end, a micrometer-screw connected to the other end of the bar to adjust the same, and a sighting-instrument adjustable longitudinally on the said bar, substantially as described.

2. In a measuring-instrument, the combination, with a pivoted base-line bar, of a sighting-instrument maintained upon said bar at a fixed angle and adjustable longitudinally thereon, and a definitely-threaded adjusting-screw for determining the angular adjustment of said bar, substantially as described.

3. A measuring-instrument consisting of a base-line bar pivoted at one end, a micrometer-adjusting-screw for moving the other end of the bar, a sighting-instrument on the said bar, and a screw for adjusting the said sighting-instrument longitudinally on the said bar, substantially as described.

In testimony whereof I have signed my name to this specification in the presence of two subscribing witnesses.

R. R. GURLEY.
